ATTORNEY

WITNESS:

UNITED STATES PATENT OFFICE.

ONESEME LANDRY, OF NEW BEDFORD, MASSACHUSETTS, ASSIGNOR TO DRAPER CORPORATION, OF HOPEDALE, MASSACHUSETTS, A CORPORATION OF MAINE.

BINDER FINGER.

Application filed January 19, 1924. Serial No. 687,293.

To all whom it may concern:

Be it known that ONESEME LANDRY, a citizen of the United States of America, residing at New Bedford, in the county of 5 Bristol and State of Massachusetts, has invented new and useful Improvements in Binder Fingers, of which the following is a specification.

This invention relates to an attachment 10 for looms, the general object of the invention being to provide a novel dagger attachment which bears yieldingly upon the binder and thereby eliminates the necessity of the spring used on the binder, holds the 15 shuttle in the box, prevents rebound, and in case of a "knock-off" prevents any crushing action upon the shuttle thru the binder.

The invention also consists in certain 20 other novel features of construction and in the combination and arrangement of the several parts, to be hereinafter fully described, illustrated in the accompanying drawings, and pointed out in the appended 25 claim.

In describing the invention in detail, reference will be had to the accompanying drawings, wherein like characters denote like or corresponding parts thruout the several views, and in which—

30 Fig. 1 is a front elevation of portions of a loom provided with the present invention;

Fig. 2 is an enlarged plan view, some of the parts being broken away, showing the invention and its relation to parts of the 35 shuttle box;

Fig. 3 is an enlarged side elevation showing the device of the present invention detached;

Fig. 4 is a rear elevation of the device; 40 and

Fig. 5 is a transverse section thru the pivotal connection of the main body of the device and the finger.

As shown in the drawings, the device 45 consists of the body 1, the finger 2, which is pivoted to the body by the bolt 3, and the spring 4, which engages the projections 5 on the body and finger and tends to hold the finger in an upright position. The body

50 1 is provided with a hole or opening 6 for receiving the dagger, which extends frontwardly from the protector rod as usual, and the body is held on the dagger by means

such as set screws 7, as shown in Figs. 3 and 4.

From the foregoing it will be seen that when the body 1 is in place on the dagger, the finger 2 will bear against the binder B, as indicated in Fig. 2, and as the shuttle enters the shuttle box the finger 2 will be 60 tilted on its pivot 3, which movement is resisted by the spring so that the spring acts as a shock absorber and thereby eliminates strain on the binder, the box, the shuttle and the dagger.

By using this device, the spring usually employed in connection with the shuttle binder may be omitted, because the spring actuated finger 2 renders such binder spring unnecessary. The spring actuated finger 2 70 holds the shuttle in the shuttle box and likewise prevents "banging off" of the loom when the shuttle properly enters the shuttle box.

Should the shuttle not properly enter the 75 box, the dagger will remain in lowered position to stop the loom as usual and at such times the yieldingly mounted finger 2 avoids any undue crushing action against the binder and finger.

It is thought from the foregoing description that the advantages and novel features of the invention will be readily apparent to those skilled in the art.

It is desired to be understood that changes 80 may be made in the construction and in the combination and arrangement of the several parts, provided that such changes fall within the scope of the appended claim.

What I claim is:—

In combination with the protector rod of a loom having a dagger, a body having an opening therein to receive the dagger rod for a connection therewith, a finger pivoted to the upper end of the body, confronting projections on the body and finger, a coil spring having its ends surrounding the projections and tending to resist movement of the finger on its pivot, and said finger having its upper end in contacting engagement with the binder of the loom for the purpose specified.

In testimony whereof I have affixed my signature.

ONESEME LANDRY.
